(57) **CLAIM**

The ornamental design for a recessed fluorescent luminaire, as shown and described.

DESCRIPTION

FIG. 1 is a bottom perspective view for a recessed fluorescent luminaire showing our new design;

FIG. 2 is a bottom plan view;

FIG. 3 is a side view of one side thereof;

FIG. 4 is a side view of the other side thereof;

FIG. 5 is a front view thereof; and,

FIG. 6 is a rear view thereof.

The broken lines shown on the drawings are for illustrative purposes only and form no part of the claimed design.

The top of the luminaire is unornamented and not visible in normal use, since it is mounted on a ceiling or other structural member. Therefore, the top of the luminaire forms no part of the claimed design and the top view has been omitted.

The broken lines which define the bounds of the claimed design form no part thereof.
